CHINAWARE STAMPING MACHINE

Gale E. Lawrence, Sebring, Ohio, assignor to
Thomas M. Barclay

Application January 31, 1942, Serial No. 429,058

10 Claims. (Cl. 101—41)

The invention relates to stamping or printing machines and more particularly to a machine for stamping surface designs upon chinaware, glass and the like.

It is an object of the invention to provide a machine which will rapidly and efficiently stamp borders or other surface designs, in gold or the like, upon china or glass plates, dishes and similar objects.

Another object is the provision of such a machine with a plurality of fingers for gripping the edges of the dishes and properly centering the same, regardless of variations in the diameters of the dishes.

A further object is the provision of automatic sizing means for regulating the diameter of the stamping head to compensate for variations in the diameters of the dishes being decorated.

A still further object is the provision of a stamping head formed of a plurality of resiliently mounted adjustable segments to which is connected the periphery of a resilient disc upon which the stamp is mounted.

Another object is the provision of a novel inking device by means of which the proper amount of gold or ink is applied to the stamp during each operation of the machine.

The above objects, together with others which will be apparent from an inspection of the drawings and the following description, may be attained by constructing the improved stamping machine in the manner illustrated in the accompanying drawings, in which—

Figure 1 is a front elevation of the improved chinaware stamping machine with parts shown in section for the purpose of illustration;

Fig. 2, a rear elevation of the machine;

Fig. 3, a side elevation of the machine with parts broken in section;

Fig. 4, a top plan view of the machine;

Fig. 5, a top plan view of a portion of the stamping head;

Fig. 6, a similar bottom plan view;

Fig. 7, a fragmentary section on the line 7—7, Fig. 5;

Fig. 8, a fragmentary plan view of the ratchet mechanism which rotates the inking plate; and

Fig. 9, a sectional view of the mechanism that feeds ink to the plate.

Similar numerals refer to similar parts throughout the drawings.

The machine is mounted upon a frame including the uprights 10, connected at their upper ends with angle iron members 11, and at a point spaced from their upper ends with the angle

irons 12, a platform 13 being supported upon the uprights at a point spaced above the floor.

Power may be furnished by a motor 14 mounted upon the platform 13 and provided with a pulley 15, connected as by the belt 16 with a pulley 17 upon the shaft 18 journalled in bearings 19 mounted upon brackets 20 supported upon the platform 13.

A graduated series of pulleys 21 is fixed upon the shaft 18 and arranged to be connected, as by the belt 22, with a similar series of pulleys 23 upon the countershaft 24, one end of which extends into the reduction gear housing 25, the other end being journalled in a bearing 26 mounted upon a bracket 27 supported upon the platform 13. The reduction gear housing 25 is suspended from the angle irons 12 as indicated at 28.

The cam shaft 29 is driven by the reduction gears and the outer end thereof is journalled in a bearing 30 mounted upon the angle iron 31 connected to adjacent uprights 10.

A large cam 32 is fixed upon the rear end portion of the cam shaft 29 and a smaller cam 33 is fixed upon the forward end portion thereof.

The bed 34 is rigidly supported at the upper end of the frame and the vertical guide rod 35 is suspended therefrom, the upper end of the guide rod being reduced as at 36 and located within a bore in the bed, a screw 37 rigidly attaching the guide rod to the bed.

The screw 37 has an extension 38 upon the head thereof and the disc 39 which supports the plate or other article to be stamped is rotatably mounted thereon being provided with a stud 40 journalled in the extension 38.

A heavy cylindric block 41 is slidably mounted upon the guide rod 35 and the plate 42 is fixed to the lower end thereof as by the screws 43 and spacers 44. A roller 45 is journalled between the ears 46 depending from the plate 42 and riding upon the smaller, forward cam 33.

For the purpose of gripping the peripheral edge of the plate or other article to be stamped and quickly centering the same, a plurality of fingers 47 are provided. Each finger is carried by a separate plate 48 adjustably mounted upon one of a series of radially disposed slidable blocks 49, as by a screw 50.

Each block 49 is slidably mounted upon a radially disposed T-shaped guide bar 51 fixed upon the bed 34.

Radial slots 52, through the guide bars 51 and bed 34, slidably receive the depending studs 53 fixed upon the blocks 49.

A plurality of radially disposed rods 54 extend outwardly from the collar 55, fixed upon the guide rod 35 above the sliding block 41.

A bell-crank lever 56 is fulcrumed upon the end of each rod 54 and connected by a link 57 with an ear 58 upon the sliding block 41, and by a link 59 with the corresponding stud 53, whereby downward movement of the sliding block 41 will simultaneously move all of the fingers 47 radially toward the center of the bed.

A vertical tubular column 60 is mounted at the rear side of the frame and extends upwardly a considerable distance above the bed 34 and slidably supports the rod 61 which is provided with the bifurcated lower end 62 in which is journaled a roller 63 riding upon the cam 32.

The forward side of the tubular column 60 is vertically slotted as at 64 to receive the key 65 which is attached to the rod 61 and the sleeve 66 as by the bolt 67 which connects the horizontal arm 68 to the sliding sleeve 66.

A bracket arm 69 may be connected to the rear side of the sleeve 66 for supporting a weight 70 to assist in holding the roller 63 in engagement with the cam 32 at all times.

The stamping head, indicated generally at 71, is carried by the horizontal arm 68, being mounted upon the depending rod 72. A circular form 73, of wood or the like, is connected to the flanged collar 74, fixed upon the lower end of the rod 72, and above said collar is slidably mounted a plate 75 fixed upon the sliding sleeve 76.

A plurality of radially disposed, inverted, U-shaped brackets 77 are mounted upon the underside of the plate 75 as by the screws 78.

The stamping head is made up of a plurality of separate segments 79, one segment being carried by each of the brackets 77, by means of a rod 80 fixed upon the inner side of the segment and slidably located through the corresponding bracket. A coil spring 81 surrounds each rod 80 and by engagement with the pin or collar 82 upon the rod, urges the segments outward.

The several segments 79 of the stamping head are flexibly connected together by a rubber diaphragm 83 which carries the rubber stamp or stamps for decorating the plates or other articles.

As indicated in Fig. 7, a border design may be provided at 84 and a second stamp at 85 for imprinting a surface decoration upon the central portion of the plate. Each of the rubber stamps 84 and 85 is preferably backed up with a soft rubber pad of sponge rubber or the like as shown at 86. A similar pad 87 is carried by the circular form 73.

The plate 75 and sleeve 76 are normally urged downward into contact with the collar 74 by the coil spring 88 which surrounds the rod 72. A ball 89 is mounted in an opening 90 in each segment 79 and held against displacement by the bracket 91, said balls being arranged for contact with the fingers 47 as will be later described.

A ring 92 is journaled upon the tubular column 60 between the fixed collars 93 and carries the bracket 94 which supports the inking plate 95.

The inking plate is rotatably mounted upon the bracket 94 and provided with a ratchet 96 which cooperates with a pawl 97 carried upon a plate 98 rotatably mounted on the bracket 94, and operatively connected to the arm 98' which is fixedly carried by one of the collars 93.

The ring 92 has a lug 99 extending radially therefrom and one end of the link 100 is pivotally connected thereto as at 101, the other end

of said link being pivotally connected at 102 to a lever 103 fixed upon the rocker shaft 104 journaled in bearings 105 and 106 upon the rear side of the frame.

5 A rocker arm 107 is fixed upon the lower portion of the rocker shaft 104 and pivotally connected as at 108 to one end of a link 109, the other end of which is pivotally connected as at 110 to a lever 111 fulcrumed at 112 upon the 10 frame.

A spring 113 is connected to the lower end of the lever 111 and to the frame to normally hold the linkage in the position shown in Fig. 2. An arcuate flange 114 is carried by the link 111 for engagement by the roller 115 upon the cam 32.

The ink is evenly distributed over the top surface of the inking plate 95 by means of an ink roller 116 formed of soft rubber and carried in a frame 117 mounted upon a carriage 118 which 20 travels upon the rails 119 by means of the upper and lower rollers 120 and 121 respectively.

The carriage is connected by a spring 122 with one arm 123 of a bell-crank lever journaled at 29, the other arm 124 of said bell-crank lever 25 being connected by the link 125 to a lever 126 fulcrumed at 127 upon the frame.

The roller 115 upon the cam 32 is adapted to engage the lever 126 and through the linkage and levers above described, the carriage 118 is 30 moved to the left as viewed in Fig. 2 rolling the soft rubber ink roll 116 across the top surface of the inking plate 95 and evenly distributing the ink thereon.

Ink is supplied to the plate 95 by means of an 35 ink container 128 supported above the inking plate upon a bracket 129 attached to the upper end of the tubular column 60. A cylinder 130 is provided upon the container and the plunger 131 in said cylinder is contacted by the lever 132, 40 fulcrumed as at 133 upon the ear 134 upon the container 128.

The lower end of this lever has a pivoted portion 135 adapted to be engaged by the upright finger 136 upon the carriage 118 for feeding ink 45 from the container onto the inking plate with each operation of the inking roller.

The lever 132 has an angular arm 137 thereon upon which is adjustably mounted a weight 138 for returning the plunger to normal position 50 after each operation thereof by the spring 130a.

With the parts in the initial position as shown in the drawings a plate or other article to be stamped is placed upon the disc 39 and as the cam shaft 29 rotates in the direction of the arrows 55 shown in Figs. 1 and 2, the roller 115 upon the cam 32 will first engage the lever 126 moving the same downward and through the link 125, bell-crank lever 123-124 and link 122, the carriage 118 will be moved to the left as viewed in Fig. 2, rolling the soft rubber roller 116 across the inking plate 95. As the finger 136 contacts the lower end 135 of the lever 132, a drop of ink will be pumped from the container 128 and deposited upon the plate 95 and as the roller 115 passes out 60 of contact with the lever 126 the spring 139 will return the carriage 118 to the initial position, the roll 116 evenly distributing the ink upon the plate 95.

In the meantime the cam 33 will have permitted 65 the sleeve 41 to move downward and through the links 57, bell-crank levers 56, and links 59, the fingers 47 will be moved radially inward gripping the peripheral edge of the plate and holding it firmly against movement.

Further movement of the cam 32 will permit

the plunger 61 to move downward moving the stamping head 71 down until the rim stamp 84 contacts the plate. Further downward movement of the rod 72 moves the soft rubber pad 87 down upon the diaphragm 83 pressing the central stamp 85 into contact with the central portion of the plate.

As the head reaches this position the rotatable balls 89 will engage the gripping fingers 47 radially moving the segments inward to size the stamp to conform to the plate, and permitting the head to be easily raised after the stamping operation.

The roller 115 will then contact the flange 114 upon the link 111 and through the rocker arm 107, rocker shaft 104, rocker arm 103, and link 100, the ring 92 will be oscillated upon the tubular column 60 swinging the inking plate 95 across the rubber stamp upon the inking head, placing sufficient ink upon the stamp for an operation.

At this time the stamping head has been raised and the fuller 63 is riding upon the high part of the cam 32, and passes through the slight depression 32a therein which drops the stamping head into contact with the inking plate.

As the roller 115 passes out of engagement with the flange 114 the spring 113 will return the inking plate to the initial position.

I claim:

1. A stamping machine of the character described comprising a bed for supporting an article to be stamped, a plurality of gripping fingers movably associated with the bed for gripping the edge of the article, means for simultaneously moving the fingers radially against the edge of the article, a vertically movable stamping head above the bed, stamping means upon said stamping head and means for moving the stamping head into contact with the article after said fingers have gripped the article and balls upon the stamping head for contact with the gripping fingers for sizing the stamping means to conform to the size of the article.

2. A stamping machine of the character described comprising a bed for supporting an article to be stamped, gripping fingers associated with the bed for gripping the edge of the article, a vertically movable stamping head above the bed, said stamping head comprising a plurality of independent segments, stamping means carried by said segments, means for moving the stamping head downward into contact with the article and means upon the segments and means upon the stamping head cooperating with said gripping fingers for radially moving the segments to size the stamping means to correspond to the article.

3. A stamping machine of the character described comprising a bed for supporting an article to be stamped, a plurality of gripping fingers movably associated with the bed for gripping the edge of the article, means for simultaneously moving the fingers radially against the edge of the article, a vertically movable stamping head, said stamping head comprising a plurality of independent segments, stamping means carried by said segments, means for moving the stamping head downward into contact with the article and balls upon the segments for contact with the gripping fingers for radially moving the segments to size the stamping means to correspond to the article.

4. A stamping machine of the character described comprising a bed for supporting an article to be stamped, a plurality of gripping fingers 75

movably associated with the bed for gripping the edge of the article, means for simultaneously moving the fingers radially against the edge of the article, a vertically movable stamping head, 5 said stamping head comprising a plurality of independent segments, spring means for urging the segments radially outward; stamping means carried by said segments, means for moving the stamping head downward into contact with the article and balls upon the segments for contact with the gripping fingers for radially moving the segments inward to size the stamping means to correspond to the article.

5. A stamping machine of the character described comprising a bed for supporting an article to be stamped, gripping means upon the bed for gripping the edge of the article, a vertically movable stamping head above the bed, said stamping head comprising a plurality of independent segments, stamping means carried by said segments, means for moving the stamping head downward into contact with the article and means upon the stamping head cooperating with said gripping means for radially moving the segments to size 10 the stamping means to correspond to the article as the stamping head is moved downward.

6. A stamping machine of the character described comprising a bed for supporting an article to be stamped, gripping means upon the bed for gripping the edge of the article, a vertically movable stamping head above the bed, said stamping head comprising a plurality of independent segments, resilient stamping means carried by said segments, means for moving the stamping head downward into contact with the article and means upon the stamping head cooperating with the gripping means for radially moving the segments to size 15 the stamping means to correspond to the article as the stamping head is moved downward.

7. A stamping machine of the character described comprising a bed for supporting an article to be stamped, gripping means upon the bed for gripping the edges of the article, a vertically movable stamping head above the bed, said stamping head comprising a plurality of independent segments, resilient stamping means means carried by said segments, means for moving the stamping head downward into contact with the article and means upon the stamping head cooperating with the gripping means for radially moving the segments to size 20 the stamping means to correspond to the article as the stamping head is moved downward and means movable vertically relative to the resilient stamping means for causing the stamping means to conform to the contour of the article.

8. A stamping machine of the character described comprising a bed for supporting an article to be stamped, a plurality of gripping fingers movably associated with the bed for gripping the edge of the article, means for simultaneously moving the fingers radially against the edge of the article, a vertically movable stamping head above the bed said stamping head comprising a plurality of independent segments, spring means for urging the segments radially outward, a resilient diaphragm carried by said segments, stamping means upon said diaphragm, means movable vertically relative to the diaphragm for causing the stamping means to conform to the contour of the article, means for moving the stamping head downward into contact with the article and means upon the segments for contact

with the gripping fingers for radially moving the segments inward to size the stamping means to conform to the article.

9. A stamping machine of the character described comprising a bed for supporting an article to be stamped, means associated with the bed for gripping the edges of the article and centering the article upon the bed, a vertically movable stamping head above the bed, stamping means upon the stamping head, means for moving the stamping head downward to contact the article and means upon the stamping head cooperating with said means for gripping the edges of the article for sizing the stamping means to conform to the size of the article as the stamping head is moved downward.

10. A stamping machine of the character described comprising a bed for supporting an article to be stamped, means associated with the bed for gripping the edges of the article and centering the article upon the bed, a vertically movable stamping head above the bed, stamping means upon the stamping head, means for moving the stamping head downward to contact the article and means upon the stamping head cooperating with said means for gripping the edges of the article for sizing the stamping means to conform to the size of the article as the stamping head is moved downward, and an inking plate for applying ink to the stamping means before each downward movement of the stamping head.

GALE E. LAWRENCE.
